UNITED STATES PATENT OFFICE.

JOHN DONNELLY, OF BRANFORD, CONNECTICUT.

HACKSAW-FRAME.

1,258,202.

Specification of Letters Patent. Patented Mar. 5, 1918.

Application filed August 28, 1917. Serial No. 188,664.

To all whom it may concern:

Be it known that I, JOHN DONNELLY, a citizen of the United States, residing at Branford, in the county of New Haven and State of Connecticut, have invented a new and useful Hacksaw-Frame; and I do hereby declare the following to be a full, clear, and exact description of the invention, such as will enable others skilled in the art to 10 which it appertains to make and use the same.

This invention relates to an improved hacksaw frame, and one of the objects of the invention is to provide a frame of this 15 kind having means whereby different lengths of blades may be held thereby.

A further object of the invention is the provision of means for holding blades of different lengths, and in planes parallel or 20 at right angles with the plane of the frame.

A further object of the invention is the provision of improved securing means for one end of said blade.

In practical fields the details of construction 25 may necessitate alterations falling within the scope of what is claimed.

The invention comprises further features and combination of parts as hereinafter set forth shown in the drawings and claimed.

30 In the drawings:—

Figure 1 is a view in side elevation of the improved hacksaw frame constructed in accordance with the invention.

Fig. 2 is a view in side elevation, showing 35 parts of the connections for the blade to frame in section, and illustrating the blade held at right angles to that shown in Fig. 1.

Fig. 3 is a detail perspective view of the 40 means for connecting one end of the blade to the frame.

Fig. 4 is a detail perspective view showing the opposite sides of the means shown in Fig. 3.

Fig. 5 is a detail perspective view of the 45 means for detachably connecting the inner end of the saw blade to the frame.

Fig. 6 is a detail sectional view on line 6—6 of Fig. 4.

Referring more especially to the drawings 50 1 designates the main bar of the hacksaw frame. This bar at its forward end is provided with an integral lateral extending part 2, which extends at an obtuse angle to the body of the bar. The outer edge of this 55 angularly extending part is constructed at right angles to the body of the bar, as shown

at 3, and is provided with a ground depression 4, the purpose of which will appear later. A cylindrical member 5 is provided, and this member is provided with longitudinally extending elongated slots 6, extending at right angles to each other, and into either one of which the end portion of the angularly extending part 2 may extend, as shown in Figs. 1 and 2 clearly. One end of this 65 member 5 is provided with a reduced ear 7, which is provided with apertures 8 and 9. These apertures 8 and 9 offset from one another angularly with respect with the longitudinal center of the member 5. One face 70 of the ear 7 is provided with a groove extending from the apertures 9 almost to the aperture 8. A fastening device 11 comprising a single length of wire is provided. This fastening device is bent upon itself to 75 form the straight portion 12, which engages the groove 10, while the arms 13 and 14 extend through the apertures 8 and 9. It is to be noted that the arm 14 after passing through aperture 9 is bent angularly and 80 forwardly toward the body of the member 5, and is adapted to pass through the aperture 15 of one end of the hacksaw blade. The other arm 13 (which passes through the aperture 8), is bent as shown, to overlie the 85 end portion of the hacksaw blade. In order to connect the hacksaw blade 16, it is disposed at right angles to the ear 7, as shown in dotted lines in Fig. 3, after which the arm 14 is passed through the aperture 15 of 90 the blade, then the blade is moved to extend in alignment with the member 5, until the arm 13 overlies the blade, as shown in Fig. 3 of the drawings. The end portion of the angularly extending part 2 of the bar 1 of 95 said frame is provided with a laterally extending lug 17 to engage the member 5, to limit the end part of the portion 2 into any one of the slots 6. The other end of the frame comprises a metallic bar 18, to which 100 a U-shaped strap 19 is riveted as shown at 20. This strap slidably receives the bar 1 of said frame, there being a laterally extending lug 21 at one end of the bar 1 to prevent removal of said strap. The bar 18 at its 105 end opposite the end having the strap 19 has secured to it by rivets 22, a metallic plate 23. This plate 23 is bent or curved to form a sleeve, which receives the shank 24 of the handle 25. It is to be noted that the shank 110 may rotate in the sleeve, and the rear marginal edge of the sleeve is provided with

scallop or recesses 26 and 27. The scallops or recesses 26 are diametrically opposite each other, while the recess 27 is at right angles to the recesses 26. The shank 24 of the handle is provided with laterally extending pins 28. The forward end of the shank 24 is cut away longitudinally to form the recess 29, and the flat face of the recess is provided with a lug 30, which extends angularly slightly rearwardly toward the handle, and as shown enters the aperture 31 at the other end of the hack saw blade. It is to be observed that when the pin 28 engages the scallops or recesses 26, the hack saw blade 15 may be held in a plane parallel with the side faces of the bar 1 of the frame, in which case the end portion of the part 2 will extend into the proper slot 6 of the member 5, whereby the end of the shank of the thumb 20 screw 32 (which is threaded into the forward end of the member 5) may engage the depression 4. Consequently by setting up on the set screw 32, and drawing the parts accordingly, the hack saw blade may be 25 tightened securely in place. It is to be noted that when the pin 28 engages the recess 27, said blade may be held on a plane at right angles to the side faces of the bar 1, and in this case the other slots 6 at right

angles to those that previously received the end portion of the part 2, may be engaged by the end portion of said part 2. By virtue of the arm 13 of the fastening means overlying the hack saw blade, said blade is held in place, until the parts are drawn secure, by adjusting the thumb screw. 35

The invention having been set forth what is claimed as new and useful is:—

In a hack saw, a frame, a hack saw blade means to connect one end of said blade to one end of said frame, the other end of said blade having an aperture, one end of said frame having an ear provided with offset disposed apertures, a securing device constructed from a single length of wire bent upon itself whereby its arms may pass through said apertures, whereby one arm may pass through the aperture of the blade, while the other arm is bent to overlie the blade. 40 45

In testimony whereof I have signed my name to this specification in the presence of two subscribing witnesses.

JOHN DONNELLY.
